J. HOGBIN AND
W. LEHMAN, INVENTORS
BY *Victor J. Evans*
ATTORNEY

UNITED STATES PATENT OFFICE.

JOSEPH HOGBIN, OF PITTSBURGH, AND WILLIAM LEHMAN, OF ASPINWALL, PENNSYLVANIA; SAID LEHMAN ASSIGNOR OF HIS ENTIRE RIGHT TO WILLIAM MARTIN, OF PITTSBURGH, PENNSYLVANIA.

CHECKER BRICK.

Application filed September 28, 1923. Serial No. 688,413.

To all whom it may concern:

Be it known that we, JOSEPH HOGBIN and WILLIAM LEHMAN, both citizens of the United States, residing at Pittsburgh and 5 Aspinwall, respectively, in the county of Allegheny and State of Pennsylvania, have invented new and useful Improvements in Checker Bricks, of which the following is a specification.

10 This invention relates to bricks, and more particularly to what we term a checker brick particularly adapted for use in constructing checkers in furnaces and similar structures.

15 One of the main objects of the invention is to provide a brick which is movably supported so that, during the use of a checker, these bricks will be caused to move slightly so as to prevent the accumulation of dust, 20 soot, ashes and other foreign materials to such an extent as to clog the checker. A further object is to provide a brick of this construction which may be readily produced and installed at small cost. Further objects will appear from the detail description.

In the drawings:

Figure 1 is a fragmentary top plan view of a checker structure showing the bricks as 25 used;

Figure 2 is a side view of the movable brick;

Figure 3 is a side view of one of the supporting bricks;

35 Figure 4 is a fragmentary side view of a checker structure showing the bricks as used.

We provide two different constructions or types of bricks, one of these, designated by 40 numeral 1 being what we term the supporting brick and being provided, at the center of the upper portion of each side, with a recess 2. Recess 2 is adapted for reception of a gudgeon 3 provided at the upper portion 45 of the end of a movable brick 4. In practice two of the supporting bricks 1 and one of the movable bricks 4 may be considered as constituting a set. Brick 4 is rockably supported between bricks 1 so as to be movable about an axis extending at right angles to the supporting bricks. The checker is built up in a known manner, supporting

bricks 1 being laid in tiers or courses, the 55 bricks of one course being staggered relative to the bricks of the next course, to form a plurality of parallel walls. Each of the 60 bricks 1 is provided in one end with a vertically extending groove 1^a and at the other end with a vertically extending tongue 1^b, the 65 bricks of each course being locked together by these tongues and grooves. As each course of supporting bricks 1 of two adjacent walls is completed, the movable 70 bricks 4 are positioned between the courses with gudgeons 3 resting in recesses 2, the 75 bricks 1 of each course serving to prevent displacement of the gudgeons 3 from the recesses 2 of the lower course. As the 80 bricks 1 of each course are staggered relative to the bricks of the next course, the rockable 85 bricks 4 of each course will also be staggered relative to the rockable bricks of the next course. The lower edge of each brick 4 is rounded at 4^a so as to provide a smooth rounded surface upon which dust and other 90 foreign materials will not readily settle. When the checker is in use the draft flowing through the checker and about bricks 4, combined with vibration incident to the operation of the furnace in connection with 95 which the checker is used, will cause a slight swinging or swaying movement of bricks 4 so as to dislodge all soot, dust and other foreign materials, to such an extent as to prevent accumulation of the same within 100 the checker, the materials thus dislodged collecting in the lower portion of the checker chamber from which they may be readily removed. In this respect the checker is self-cleaning and clogging or choking of the checker due to the accumulation of soot, 105 ashes and other foreign materials is eliminated.

What we claim is:-

1. In a checker structure, in combination 95 with spaced supporting walls, cross members rockably supported between said walls for swinging movement about axes disposed substantially at right angles to the walls.

2. In a checker structure, a plurality of 100 parallel supporting walls, and cross members rockably supported in spaced relation between said walls.

3. In a checker structure, two parallel

2 supporting walls formed of bricks provided in their lateral faces with recesses, and cross bricks provided with gudgeons fitting into said recesses and rockably supporting said cross bricks between the bricks of the walls.

4. As an article of manufacture, a checker brick provided at each end with a gudgeon

of circular cross-section adapted to fit into a corresponding recess provided in the lateral face of a supporting brick.

In testimony whereof we affix our signatures.

JOSEPH HOGBIN.

WILLIAM LEHMAN.
